UNITED STATES PATENT OFFICE.

ELsie DINSMORE LANDFEAR, OF JERSEY CITY, NEW JERSEY.

DESIGN FOR A RAG DOLL.

Application filed May 24, 1924. Serial No. 9,703. Term of patent $3\frac{1}{2}$ years.

To all whom it may concern:

Be it known that I, Elsie DINSMORE LANDFEAR, a citizen of the United States, residing at Jersey City, in the county of Hudson and State of New Jersey, have invented a new, original, and ornamental Design for a Rag Doll, of which the following is a specification, reference being had to the accompanying drawing, forming part thereof.

The figures are a front and side view of a doll, showing my new design.

I claim:

The ornamental design for a rag doll as shown.

ELsie DINSMORE LANDFEAR.
